UNITED STATES PATENT OFFICE

HOWARD D. SALISBURY, OF BIRMINGHAM, ALABAMA

ELECTRODE SUPPORT FOR DUST PRECIPITATORS

Application filed October 8, 1929. Serial No. 398,189.

This invention relates in general to improved structural features in precipitation apparatus wherein electrostatic discharges of high voltage from a charged electrode cause a separation of dust particles or the like from a gaseous body in which such particles are suspended. The invention aims to provide an improved insulated electrode supporting structure to which access can be had for the purpose of making examination or repairs; to provide a support-containing chamber, which is normally in communication with the main chamber through which the dust laden gases flow, but which dust support-containing chamber can be isolated from the main chamber without stopping the flow of gas through the latter whenever it may be desired to inspect the electrode support, to clean it, to remove it, or to replace it. The invention also aims to provide means, which will return the units of a discharging electrode to their proper relative position after they have been thrown out of proper location; and to provide temporary supporting means for a discharge electrode, which are adapted to be brought into play when removing or replacing an electrode supporting insulator.

The invention also provides means whereby the discharge electrode is automatically grounded through the structure of the apparatus, when the support-containing chamber is isolated from the main chamber, thereby dissipating any static electric charge within the apparatus and also protecting workmen in the event that the electrical power should be accidentally supplied to the discharge electrode circuit while workmen are engaged in repairs.

The invention will be fully apparent from the following specification when read in connection with the accompanying drawings and the features of novelty will be defined with particularity in the appended claims.

In the drawings:

Fig. 1 is a plan view showing the apparatus with cover removed from main chamber;

Fig. 2 is a vertical section on line 2—2 of Fig. 1;

Fig. 3 is an enlarged vertical section on

lines 3—3 of Figs. 1 and 5 showing doors open;

Fig. 4 is an enlarged vertical elevation on line 4—4 of Fig. 1;

Fig. 5 is a sectional plan on line 5—5 of Fig. 4;

Fig. 6 is a section of the lower part of Fig. 3 showing the doors closed;

Fig. 7 is a sectional plan on line 7—7 of Figs. 2 and 3.

Figs. 8 and 9 are detail sectional views illustrating modifications.

Referring in detail to the drawings, 11 is a main chamber through which the gas to be treated is passed, having within it discharge electrodes 12 and collecting electrodes 13. The discharge electrodes are supported at four corners by insulators 14 to which hang supporting rods 15 that have collars 16 fastened to them. Holes are provided in main chamber 11 for the supporting rods 15 to pass through and these holes are closed by doors 17 and 18 to close off or isolate auxiliary chambers 19 from the main chamber 11 when it may be desired to do so. The auxiliary chambers 19 are formed in housings having walls 19^a and 19^b as shown. Supporting rods 15 are threaded at their top ends and pass through holes in the insulators 14, nuts 20 being provided to adjust and support said rods. At 21 is shown a power supply line fastening under nut 20 to one of the supporting rods 15. 22 are covers over insulators 14. 23 are manhole covers held in place by swinging bolts 24, the manholes providing openings through walls 19^a so that the underside of insulators 14 may be inspected and cleaned. The insulator covers 22, as shown at 22^a, are bolted to the walls 19^a.

The top portions of the insulators may be inspected and cleaned or the insulators removed entirely by simply removing the covers 22 or in the case where a conduit is provided for power line, the insulators may be inspected and cleaned through manhole openings in the walls 19^a and replaced through openings in the conduit, which are formed by removable sides as indicated at 25. Door 17 is fastened to shaft 26 by key 27 and is operated by means of a lever 28 fastened to shaft by key 29. Door 18 is

fastened to shaft 30 by key 31 and is operated by means of a lever 32 fastened to shaft by key 33. A bolt 34 fastens lever 28 to fixed bracket 35 to hold door 17 in closed position and in similar manner a bolt 36 fastens lever 32 to fixed bracket 37 to hold door 18 in closed position.

When doors 17 and 18 are in open position levers 28 and 32 are in the dotted position shown in Fig. 4.

10 Doors 17 and 18 are notched as shown in Fig. 5 and rods 15 are brought to proper location by the notches although they may have been shifted out of place by an irregular failure of an insulator.

15 Ordinarily doors 17 and 18 are open and chambers 19 are open to main chamber 11, with levers in dotted position shown in Fig. 4, but when it may be desired to inspect, clean,

20 remove or replace an insulator the power supply is cut off and doors 17 and 18 are closed by throwing levers 28 and 32 into position indicated by full lines on Fig. 4 and the doors are then locked in closed position by means of bolts 34 and 36 and brackets 35 and 37.

25 In this manner chambers 19 are cut off and isolated from the main chamber 11, so that manhole covers 23, insulator covers 22 and part 25 can be removed as may be desired.

30 Reference to Fig. 6 shows how the doors 17 and 18 when locked in their closed positions form supports for collars 16, which in turn support the discharge electrode. When the said electrodes are thus supported, the nuts 38 35 may be removed to disengage insulators 14 so that they may be removed and replaced without difficulty.

35 As a safety measure after the manholes have been opened sand or suitable plastic 40 materials are placed on top of the closed doors 17 and 18 to provide a gas seal that will not leak.

40 From the foregoing it is clear that when the doors 17 and 18 are in the closed position of Fig. 6 the chambers 19 through which the 45 electrode supporting rods 15 extend will be isolated from the main separating chamber 11, through which the gas to be treated is flowing. By closing the doors 17 and 18 and locking them in closed position as described 50 it is apparent that by coaction with the collars 16 the weight of the electrodes 12 may be taken by the doors instead of by the insulators 14. In short, when the doors are closed the 55 insulators may be relieved of the weight of electrodes 12. This permits of easy and quick removal and replacement of the insulators 14. During the replacement of the insulators, the doors by virtue of the notched or slotted ar- 60 rangement described serve to accurately spot or locate the supporting rods 15 so that when a new insulator is applied it can be accurately installed so as not to disturb the proper relative position between the electrodes 12 and 13.

65 It is also clear that during the time of change

of insulators when doors are closed there will be a metallic connection between the supporting rods 15 and the other metallic parts of the structure. The structure as a whole is usually grounded electrically. This contact 70 between the doors and the rod 15 and collar 16 serves as a safety feature to ground the supporting rods 15 while repairs are being made. This serves to dissipate any static electric charge within the apparatus and also 75 serves to protect workmen engaged in making insulator adjustments or replacements in the auxiliary chamber 19 in the event that the electrical power should accidentally be supplied to the discharge electrode circuit. 80

The discharge electrodes 12 and collecting electrodes 13 are of known construction. The collecting electrodes frequently being made in the form of a series of plate-like slabs of concrete or the like. These collecting electrodes are usually grounded to the metallic parts of the apparatus. The discharge electrodes are usually in the form of suspended bars, which carry a plurality of wires or chains. The discharge electrodes are located between the 85 slabs or plates of the collecting electrodes. The current for the precipitator is provided in the usual manner and the means for supplying such current is merely diagrammatically indicated in Fig. 2 as this current supply means forms no part of the present invention and is well known to those skilled in the art. 90

Fig. 8 illustrates a slight modification wherein the casing of Fig. 3 enclosing the auxiliary chamber 19 is omitted. In the construction of Fig. 8, the insulator 14 rests directly on lugs 14^a of a casting 14^b secured to the top of the precipitating casing. The other parts are substantially the same as described in connection with Fig. 3 and are correspondingly numbered. 100

Fig. 9 illustrates a construction wherein an insulator 40 is supported on a bracket 41 located on the outside of a casing 42. The insulator 40 supports a conductor 15^a, which extends into a chamber 43. Communication between the chamber 43 and the outer atmosphere is normally closed by a disc of insulating material indicated at 45 which is detachably secured by members 44 held by bolts 46. 110

In this construction doors 17^a and 18^a may be closed so as to support the conductor 15^a when the closure member 45 is removed. The casing 42 may be considered as a substantial 120 equivalent of the casing enclosing the precipitator chamber 11 referred to in connection with Figs. 1 and 2.

Various modifications may be made by those skilled in the art without departing 125 from the invention as defined in the appended claims.

What I claim is:

1. An apparatus comprising two chamber structures normally in communication, nor- 130

- mally open movable closure members controlling such communication, an electric conductor normally supported by one of said structures and adapted to be supported by 5 said closure members when they are closed.
2. An apparatus comprising two chamber structures normally in communication, normally open movable closure members controlling such communication, an electric conductor having a portion for coaction with said closure members whereby it is supported by the closure members when the latter are closed, and means for holding said closure members in closed position.
- 10 3. An electric precipitator having a main casing forming a treating chamber, a collecting electrode structure and a discharge electrode structure therein, a housing forming an auxiliary chamber communicating with said 20 treating chamber, supporting means for one of said electrode structures passing through said auxiliary chamber and pivotally mounted members for closing communication between the main treating chamber and said 25 auxiliary chamber.
4. An electric precipitator having a main casing forming a treating chamber, a collecting electrode structure and a discharge electrode structure therein, a housing forming an 30 auxiliary chamber normally in communication with said treating chamber, normally open movable closure members controlling such communication, supporting means for one of said electrode structures passing 35 through said auxiliary chamber, said supporting means adapted to be supported by said closure members when closed and means for holding said closure members in closed position.
- 40 5. An electric precipitator having a main casing forming a treating chamber, a collecting electrode structure and a discharge electrode structure therein, a housing forming an auxiliary chamber communicating with said 45 treating chamber, supporting means for one of said electrode structure connected to a current supply and means for closing communication between the main treating chamber and said auxiliary chamber, said closing 50 means when closed serving to ground said electrode.
6. An electric precipitator having a main casing forming a treating chamber, a collecting electrode structure and a discharge electrode structure therein, a housing forming an auxiliary chamber communicating with said 55 treating chamber, supporting means for one of said electrode structures and movable doors for closing communication between the 60 main treating chamber and said auxiliary chamber, said closing means when closed coacting with said supporting means to locate said electrode structure.
- 65 7. An electric precipitator having a main chamber structure and an auxiliary chamber structure and complementary doors for isolating the interiors of the said chamber structures.
8. An electric precipitator having a main chamber structure with an electrode structure therein, an auxiliary chamber structure carrying an insulator, a conductor supported by said insulator and sustaining said electrode structure and movable doors adapted to temporarily engage and support said conductor when said insulator is removed for replacement or repair. 70
9. An electric precipitator having a main chamber structure with an electrode structure therein, an auxiliary chamber structure carrying an insulator, a conductor supported by said insulator and sustaining said electrode structure and a grounded member adapted to temporarily engage and support said conductor when said insulator is removed for replacement or repair. 75
10. An electric precipitator having a main chamber structure with an electrode structure therein, an auxiliary chamber structure carrying an insulator, a conductor supported by said insulator and sustaining said electrode structure and means arranged to ground and support said conductor and thus to permit handling of the insulator and conductor with safety. 80
11. An electric precipitator having a main chamber structure with an electrode structure therein, an auxiliary chamber structure carrying an insulator, a conductor supported by said insulator and sustaining said electrode structure and means for closing communication between the main chamber and auxiliary chamber, said means being movable into engagement with said conductor. 85
12. An electric precipitator having a collecting and a discharge electrode structure therein, supporting means for the discharge electrode structure including an insulator and a member adjustable longitudinally of said insulator and sustaining said electrode structure whereby the discharge electrode is accurately positioned with relation to the collecting electrode. 90
13. An electric precipitator having a plurality of insulator supporting a discharge electrode within a main treating chamber, housings for the insulators which form chambers normally in communication with the main treating chamber, closure means which operate to close the opening between said chambers and the main treating chamber, said insulators arranged to support the discharge electrode through supporting members some of which also serve as line conductors to supply electric current to said discharge electrode. 100
14. An electric precipitator having a collecting and a discharge electrode structure therein, insulating means for supporting the discharge electrode structure, means for lo- 110
- 120
- 125
- 130

cating and supporting said discharge electrode structure when the insulating means is being replaced, said locating and supporting means also being arranged to prevent the escape of gas from the precipitator.

15. An electric precipitator having a collecting and a discharge electrode, a plurality of insulated supporting means for the discharge electrode structure, and adjustable means extending longitudinally through said insulating supporting means for positioning the discharge electrode in proper relationship to said collecting electrode.

16. An electric precipitator having a plurality of collecting electrodes and a plurality of discharge electrodes, a supporting frame to which said discharge electrodes are connected, a plurality of insulating means supporting said frame, means for adjusting said frame with respect to said insulating coating complementary members whereby the discharge electrodes can be properly positioned with relation to said collecting electrodes.

In witness whereof, I have hereunto signed
25 my name.

HOWARD D. SALISBURY.
